UNITED STATES PATENT OFFICE.

SAMUEL DARLING, OF PROVIDENCE, RHODE ISLAND.

GAS HEATING APPARATUS.

SPECIFICATION forming part of Letters Patent No. 253,850, dated February 21, 1882.

Application filed July 12, 1881. (Model.)

To all whom it may concern:

Be it known that I, SAMUEL DARLING, of Providence, Rhode Island, have invented a new and useful Improvement in a Gas Heating Apparatus for Domestic and other Purposes; and I hereby declare that the following, taken in connection with the drawings which accompany and form part of this specification, is a full, clear, and exact description of the invention, which will enable others skilled in the art to which it appertains to make and use the same.

The object of my invention is to make a gas heating apparatus that will produce more complete combustion of gas and be more convenient and economical than any heretofore in use, and which can be run with the least as well as with the largest amount of gas required for domestic purposes; and it consists in making a gas-burner in which the gas and air are united in the right proportion to produce the most effective combustion when the largest as well as the least quantity of gas is being used; a burner without perforated plate at the burning-aperture, having a single narrow and continuous combustion-aperture, and in which the gas will not take fire in the gas-chamber with the least pressure of gas; a burner in which the gas and air will be heated to a high degree before combustion; a double gas-burner having two gas and air chambers and two gas-cocks so arranged that both may be run together or either one without the other; a double burner with one part larger than the other; a ring gas-burner, the gas being burned on the inside and outside of the ring; a burner having a gas-deflector in the mixing-chamber against which the gas impinges as it enters; a gas-burner having a regulator to regulate the quantity of air to be mixed with the gas, the regulator being moved automatically as the gas-cock is turned; and also a gas-burner having a radiator which is a slow conductor of heat, to receive the heat thrown outward from the gas and radiate it back upon the kettle or article being heated.

The use of gas for cooking and other purposes is rapidly increasing. Though more expensive than oil it is much more convenient, cleanly, and safe, and the more wealthy class

of people will use it instead of oil. Oil-stoves require a great deal of attention and labor to keep them in order, and doubtless the time it takes to keep the oil-stove in good working condition is worth more than the difference in the cost of gas and oil.

One great defect in the gas-burners now in use is that a burner burning sufficient gas for domestic purposes generally cannot be run with as little gas as is required to be most convenient and economical for many domestic uses. To remedy that defect I make a burner in two parts, one part being much larger than the other, and so arranged that both parts can be run together or either part without the other, the smaller part requiring an extremely small quantity of gas to run it.

With the burners now in use the flame is not evenly spread over the surface of the article being heated. With my burner the heat can be applied evenly all over the bottom of the kettle or article being heated, or applied according to the work being done.

In most gas-burners in use the flame is not sufficiently steady, and especially when little gas is being used. In my improved burner the flame is perfectly steady when the least gas is being used, and it produces more complete combustion of gas than any within my knowledge with less offensive odors.

Another defect in the gas-burners heretofore in use is that the air is not mixed with the gas in the right proportion; but in my burner there is a regulator which can be adjusted to regulate the ingress of the air to agree with the quantity of gas used, and there is also a great loss of heat in the burners heretofore in use from outward radiation from the flame, which I prevent in my burner by having a radiator which is a slow conductor of heat, to receive the heat radiated outward from the flame, and throw it back upon the article being heated, the radiator soon becoming very hot and adding much to the heat of the gas.

In the accompanying drawings I have illustrated a gas-heating apparatus embracing my improvement, in which—

Figure 1 represents a top view of a single-ring burner; Fig. 2, a vertical central section of a single-ring burner and part of the gas and

air chamber; Fig. 3, a vertical central section of a single-ring burner having a radiator and kettle; Fig. 4, a vertical central section of a single-ring burner having a radiator, flat-iron, 5 and flat-iron protector; Fig. 5, an air-regulator; Fig. 7, a horizontal section of a double-ring burner through line $\alpha\alpha$; Fig. 8; Fig. 8, a vertical central section of a double-ring burner.

The letter A represents a hollow-ring gas-
10 burner made in two parts and fastened together with screws D; B, the central part of the ring and the smaller part of the burner; C, inlet gas and air pipe and mixing-chamber; D, screws that hold the two parts of the burner 15 together; E, combustion-aperture; F, lower part of a slow-conductor radiator; G, upper part of the same; H, a kettle; I, frame that supports the radiator and kettle or other article being heated. The radiator is made in two 20 parts, the lower part being fixed and the upper part removable and changeable in size and shape to fit different articles to be heated. J is a flat-iron; K, an iron to keep the blaze from the flat-iron; L, a radiator adapted to heating 25 flat-irons; m, arms attached to frame I, which, in connection with the projections n, support the kettle or article being heated; O, the interior of the larger part of the burner; P, the interior of the smaller part of the burner; Q, 30 slotted ring outside of the gas and air pipe and mixing-chamber R, which is also slotted to correspond with the slots in the ring Q; S, gas-deflector to spread and mix the gas with the air as it enters; T, gas-cock; U, perforated plate 35 placed at a distance from the burning-point in that form of burner to more thoroughly mix

the gas and air; V, projection on the handle of the gas-cock that turns the slotted ring Q; W, the gas and air pipe and mixing-chamber to the smaller part of the burner P; Z, the gas 40 and air pipe to the outer and larger part of the burner O.

My improved burner may be made of iron or any suitable material. The slow radiator is made of clay, preferably, and fired like fire-brick. The opening (aperture) at the burning-point is about one-fortieth of an inch. The partition Y between the two parts of the double burner may be made gas-tight by facing off the two surfaces, so that they will make a good 45 joint when screwed together, or by any other known means of doing such work.

Having described my invention, what I claim, and desire to secure by Letters Patent, is—

1. A gas-burner having two narrow continuous combustion-apertures, one larger than the other, the larger one being in the outer and the smaller one in the inner contour of the burner, substantially as described. 55

2. A double gas-burner in one piece, having 60 in combination two combustion-apertures, one larger than the other, the larger one in the outer and the smaller one in its inner contour, a partition within the burner dividing it into two gas-chambers, and a supply-pipe and gas-cock for each chamber, substantially as described. 65
